DESIGN FOR A BASE FOR A DESK SET OR THE LIKE

Gustav J. Sengbusch, Milwaukee, Wis.

Application October 5, 1936, Serial No. 65,166

Term of patent 7 years

To all whom it may concern:

Be it known that I, Gustav J. Sengbusch, a citizen of the United States, residing in Milwaukee, county of Milwaukee, and State of Wisconsin, have invented a new, original, and ornamental Design for a Base for a Desk Set or the like, of which the following is a specification, reference being had to the accompanying drawing, forming a part thereof.

Fig. 1 is a plan of a base embodying my new design;

Fig. 2 is a side elevation of the base; and

Fig. 3 is an end elevation of the right-hand end of the base as shown in Figs. 1 and 2.

I claim:

The ornamental design for a base for a desk set or the like substantially as shown.

GUSTAV J. SENGBUSCH.
